UNITED STATES PATENT OFFICE.

JAMES C. MOCK, OF DETROIT, MICHIGAN.

CARRIER SUPPORT FOR SWITCH AND SIGNAL RODS.

Application filed November 15, 1924. Serial No. 750,186.

My invention relates to an improvement in the means for supporting the brackets or carriers of switch or signal operating rods or elements and relates more particularly to the supports or pedestals and the carrier supporting elements mounted on the pedestals and to which the carrier brackets are secured.

The invention has for its object the provision of a construction which possesses the necessary strength to withstand or resist the thrusts encountered in the operation of the switch or signal operating elements or rods.

The invention also has for its object the provision of a construction which may be readily put into place and wherein the carrier supporting bars or members will be easily and at the same time rigidly secured on the pedestals; my invention providing a construction which will enable the use of what is known as commercial angle iron whereby the pipe or rod carriers are supported and secured in place; and therefore a construction wherein the height of the assembled structure will be less than that of a construction wherein channel irons are employed for supporting the carriers as in constructions at present in use.

The objects and advantages of my invention will all be more fully comprehended from the detailed description of the accompanying drawing, wherein:

Figure 1 is a perspective view of my complete carrier support shown mounted in place, with portions of the carrier supporting elements or bars and a carrier shown in position.

Figure 2 is a perspective view of the main supporting member or pedestal.

Figure 3 is a perspective view of a modified form of pedestal or supporting member.

Figure 4 is a perspective view of a complete pipe carrier support employing the pedestal shown in Figure 3.

The carrier supports or pedestals are usually mounted on and secured to a suitable pier or foundation generally constructed of concrete, as indicated for example at 10, to which the pedestal, shown at 11, is secured in any suitable manner, as for example by means of a hook-bolt or rod shown at 12, the lower end whereof extends into a suitable socket in the side of the concrete foundation, while the upper end is disposed

through an opening in the extended lobe or ear 13 of the pedestal 11.

The pedestal 11, which is preferably of cast metal, comprises a base 14 provided with the bearing surfaces or foot portions 15, 15 at opposite ends. The pedestal is shown formed with the upwardly and outwardly curved or sloping end walls 16, 16. In order to provide a comparatively light structure, I have shown the pedestal of the more or less skeleton formation and therefore provide the reinforcing webs 17, 17 extending upwardly from the base 14, at points intermediate of the ends of the base, to a height equal to that of the webs 17, 17 and in spaced relation therewith. The ends 16, 16 and the webs 17, 17, at each end of the pedestal, are formed integral with the upper end portions 18, 18.

The one longitudinal side of the pedestal, namely what may be termed as the inner longitudinal side, relative to the manner of assembling the parts, is provided with a vertically disposed wall or web 19 extending from end to end formed integral with the base 14, the webs 17, and the ends 16 and the upper end portions 18. As is apparent from the construction shown and described, a comparatively light pedestal is thus provided, which at the same time will possess the requisite strength and rigidity.

The vertical wall or web 19 at suitable points removed from the ends 18, namely at points coincident with the more or less horizontally disposed portions of the webs 17, 17, is provided with a pair of grooves or notches as at 20, 20, that is to say a groove or notch 20 adjacent to each end 18, which is adapted to receive and provide a seat for one leg or side of each angle bar 21, to which the brackets or carriers 22 are secured.

The upper end portions 18, 18 are each preferably provided with a recessed surface as at 23 to provide a seat for the other leg or side of the angle bar 21 and thus also provide a shoulder or abutment for the outer longitudinal side of the bar 21. The recesses are preferably each of a depth equivalent to the thickness of the leg or side of the angle so that the side or leg of the angle may extend flush with the upper surface of the major portion of the ends 18 as shown in Figure 1.

As is evident from the construction shown, the grooves or notches 20, 20 and the

shoulders formed by the recessed surfaces 23 will maintain the angle bars in place against lateral or sidewise movement. The angle bars 21, 21 are in turn secured to the pedestal against longitudinal movement by means of the nuts 24 secured to the bolts 25 (or by the heads of the bolts) which extend upward through suitable apertures formed in the upper end portions 18 at points adjacent to the recessed surfaces 23; the heads of the bolts being disposed in the recesses or sockets formed intermediate of the ends 16 and the reenforcing webs 17; these recesses being sufficiently large to permit insertion of the bolts while at the same time holding the heads of the bolts (or the nuts as the case may be) against accidental rotation.

The angle bars 21 are provided with a number of perforations or openings 26 at suitable spaced intervals apart to correspond with the usual spacing of the brackets of the carrier 22, and the apertured foot-portions thereof so that the foot portions of the brackets may be bolted to the angle bars by means of the bolts 27 as shown in Figure 1.

In the modification of the invention, disclosed in Figures 3 and 4, the pedestal, which is also preferably of cast metal, comprises a base portion 28, preferably provided with the bearing surfaces or foot portions 29 at opposite ends. The pedestal is shown provided with upwardly and outwardly curved or sloping end walls 30, 30 preferably of width commensurate with the width of the base. The end wall portions are shown terminating at top in the horizontally disposed surfaces 31 extending inwardly or toward each other from opposite ends of the pedestal and also preferably formed integral with a connecting top or reenforcing web 32. The connecting web or top portion 32 is preferably in a plane beneath the plane of the end surfaces 31; and this web 32, the end walls 30 and their surfaces 31, together with the base portion 28 are all preferably formed integral, at one side of the pedestal, with a side wall 33.

The top reenforcing web 32 is preferably reenforced by means of the integral vertically disposed webs 34, 34, which in turn are formed integral with the base portion 28 at points intermediate of the ends of the base and preferably at a point where the base 28 is provided with the extended lobe or ear 35 which projects beyond one side of the pedestal. The lobe or ear 35 is apertured to receive the hook-bolt or rod 12, whose lower end usually extends into a suitable socket formed in the side of the concrete foundation indicated at 10 on which the pedestal rests when in assembled position.

The end walls 30 and the downwardly

curved portions of the top reenforcing web 32, like the end walls 16 and the web 17 in Figures 1 and 2, are arranged in spaced relation to provide nut or bolt-head receiving sockets beneath the top surfaces 31; the surfaces 31 being apertured at 36 to receive bolts 37 whereby the supporting rods or angle bars 38, which extend transversely of the pedestals at both ends thereof, are clamped in place. The side wall 33 and the top reenforcing web 32, like the side wall 19 and reenforcing webs 17 in Figures 1 and 2, are preferably disposed a sufficient distance beneath the plane of the upper end surfaces 31, to correspond with the width of one side or leg of the supporting angle bars 38, to permit the one leg or side to be disposed vertically and to rest on the top reenforcing web 32, while the other side or leg is disposed horizontally and rests on the top end surfaces 31. The top end surfaces 31, like in the pedestal shown in Figures 1 and 2, are each preferably slightly recessed as at 39 to provide an abutting surface at the inner sides of the top surfaces and therefore to one side of the bolt-receiving holes 36.

The top reenforcing surface or web 32, at points in proximity to the ends of the pedestal, is provided with the shoulders or lugs 40, 40 to provide stops or abutments for the vertically disposed sides or legs of the angle bars 38 and thus prevent transverse movement of the angle bars in one direction; transverse movement of the bars 38 in the opposite direction being prevented by the shoulder formed by the recess 39 as well as by the bolt-head or nuts. The angle bars 38 in the construction shown in Figures 3 and 4 have the horizontally disposed sides or legs shown provided with the key-hole slots 41 to receive the bolts 27 whereby the brackets or carriers 22 are secured in place; the slots compensating for any inaccuracies that may occur in the castings and thus enabling easy assembly.

The construction shown in Figures 3 and 4, like that shown in Figures 1 and 2, provides a comparatively light pedestal of more or less skeleton form and therefore not of excessive weight, while at the same time possessing the requisite strength required to withstand the shocks and strains to which it is subjected; and while the constructions illustrated are believed to be the simplest and best adaptations of my invention and have been described in terms employed merely as terms of description and not as terms of limitation, structural modifications are possible and may be made without, however, departing from the spirit of my invention.

What I claim is:

1. In a carrier support, a pedestal comprising an integral structure provided with

a base having a side wall integral with one longitudinal side of the base, upwardly extending end walls terminating in horizontal surfaces adapted to extend beyond the vertical plane of and above said side wall, the horizontal top surfaces of the ends and upper edge of said side wall at points adjacent to the ends being each provided with abutting surfaces for the longitudinal edges of 10 carrier supporting rails.

2. In a carrier support, a pedestal comprising a base provided with a bolt-receiving aperture, upwardly and outwardly disposed ends terminating in horizontally disposed upper surfaces recessed adjacent to the inner ends to provide transverse shoulders, the ends beyond said recesses having

bolt-receiving apertures, an upstanding side wall, integral with one longitudinal side of the base and extending from end to end and terminating in a plane beneath that of said recessed portions of the ends, the upper surface of said side wall adjacent to each end being provided with rail holding surfaces, in combination with a pair of angle bars 25 disposed intermediate of the ends of the pedestals, each angle bar being arranged with one side seated on the recessed portion of the pedestal ends in abutting relation with said shoulders while the vertically disposed side of each bar rests edgewise on said side wall in contact with the adjacent rail holding surface. 30

JAMES C. MOCK.

CERTIFICATE OF CORRECTION.

Patent No. 1,681,619.

Granted August 21, 1928, to

JAMES C. MOCK.

It is hereby certified that error appears in the printed specification of the above numbered patent requiring correction as follows: Page 3, line 28, claim 2, after the word "side" insert the words "disposed horizontally and"; and that the said Letters Patent should be read with this correction therein that the same may conform to the record of the case in the Patent Office.

Signed and sealed this 25th day of September, A. D. 1928.

(Seal)

M. J. Moore,
Acting Commissioner of Patents.
